Attorney.

UNITED STATES PATENT OFFICE

147,292

DESIGN FOR A COMBINATION TOOTH- BRUSH AND GLASS HOLDER

Robert F. McKee, Los Angeles, Calif.

Application March 23, 1946, Serial No. 127,830

Term of patent 14 years

(Cl. D4—3)

To all whom it may concern:

Be it known that I, Robert F. McKee, a citizen of the United States, residing at Los Angeles, in the county of Los Angeles and State of California, have invented a new, original, and ornamental Design for a Combination Toothbrush and Glass Holder, of which the following is a specification, reference being had to the accompanying drawing, forming part thereof.

In the drawing

Fig. 1 is a top plan view of a combination toothbrush and glass holder, showing my new design;

Figure 2 is a side elevation of the device shown in Figure 1; and

Figure 3 is an end elevation of the device shown in Figure 1.

I claim:

The ornamental design for a combination toothbrush and glass holder, as shown.

ROBERT F. MCKEE.
